UNITED STATES PATENT OFFICE.

WILLIAM F. BEECHER, OF CLEVELAND, OHIO.

HEATING AND VENTILATING.

SPECIFICATION forming part of Letters Patent No. 236,141, dated January 4, 1881.

Application filed June 29, 1880. (No model.)

To all whom it may concern:

Be it known that I, WILLIAM F. BEECHER, of Cleveland, in the county of Cuyahoga and State of Ohio, have invented certain new and useful Improvements in Heating and Ventilating; and I do hereby declare the following to be a full, clear, and exact description of the invention, such as will enable others skilled in the art to which it pertains to make and use it, reference being had to the accompanying drawings, which form part of this specification, and in which—

Figure 1 is a vertical sectional view of the ventilating stack, showing the manner of connecting the same with the different rooms of a building. Fig. 2 is a vertical sectional view, in plane x x of Fig. 3, of the passage which incloses the heat-conducting pipes and ventilating-stack. Fig. 3 is a view, in front elevation, of the heat-conducting pipes, the ventilating-stack, and the furnace, said view having the front wall of the passage which incloses said pipes and stack removed, and also having the wall of the heating-chamber removed. Fig. 4 is a plan view of the third floor of a building, showing, in cross-section, the ventilating-stack, and also the heat-pipes. Fig. 5 is a plan view of the second floor of a building, showing, in cross-section, the ventilating-pipe, and also the heat-pipes leading to the second and third floors. Fig. 6 is a plan view of the first floor of a building, showing, in cross-section, the ventilating-pipe and heat-pipes leading to the first, second, and third floors. Fig. 7 is a plan view of the basement of the same building, showing, in cross-section, the ventilating-stack, and also the position of the furnace and hot-air chamber. Fig. 8 is a vertical sectional view of the ventilating-pipe, showing, also in section, my improved mechanism for connecting the ventilating-pipe with the rooms. Fig. 9 is a view, in transverse section, of Fig. 8 on the line x y . Fig. 10 is a detached vertical sectional view of a portion of one of the heating-pipes, to which is attached my improved adjusting-plate for regulating the supply of hot air. Fig. 11 is a plan view of my improved mechanism for regulating the amount of heat discharged from the hot-air chamber into the heat-pipe. Fig. 12 is a plan and vertical sectional view of the adjusting-

plate detached from its collar-plate. Fig. 13 is a detached view, in cross-section, of the collar-plate, adapted to hold the adjusting-plate shown in Fig. 12, and within which it slides. 55

In said drawings, A represents the heating-chamber; A', the furnace, which is provided with a pipe, a , for the passage of smoke and gas. This pipe a passes through the ventilating-stack B. This ventilating-stack extends from the basement to the roof, and the object of placing the smoke-pipe within the ventilating-stack is to heat the air within and cause an upward draft. Connected with this ventilating-stack are apertures B' upon each 65 of the several floors of the building.

In Figs. 8 and 9 are shown, in detail, the manner of connecting the apertures B' with the ventilating-stack. This consists of a tube, of any desired material or construction, the only 70 essential feature being that it is closed in all parts, save at the entrance B' and at its upper portion where it opens directly into the ventilating-stack.

As shown in Fig. 3, each floor of the building is connected with the furnace-room by separate pipes C'. These heating-pipes C' terminate at the upper portion of the room. 75

It is a well-known fact that when different floors of a building are to be heated, all other 80 things being equal, the upper room of the building will receive the greatest amount of heat. This is due to the fact that the pipe leading thereto is longer and the draft consequently better. To avoid this difficulty I have 85 constructed the device shown in Figs. 10, 11, 12, and 13. This device consists in providing an adjustable opening attached to each pipe. The object of this adjustable opening is to permit the operator to regulate the point in 90 the hot-air chamber from which heat should be conveyed to each floor. The greatest amount of heat will be stored in the upper portion of the hot-air chamber. The consequence is, that the pipe leading to the first floor being shorter, 95 and its draft consequently less, it should receive its supply from the upper portion of the hot-air chamber, while the pipe leading to the upper floor being longer and draft greater, said pipe should receive its supply from a 100 point below that from which it is taken for the first floor. Any intermediate floors should

receive their supply at points between the first and upper floors. My device for regulating the supply consists of a plate, D, having an oblong hole or groove in one side thereof, 5 and a flange upon each edge, within which the collar-plate E may slide. This collar-plate E is connected by an elbow with the heat-pipe C in such a manner as to permit of its vertical adjustment.

10 I do not limit myself to the specific construction of this portion of my device. Other forms of connection and adjustability might easily be made.

15 I prefer to construct my ventilating-chamber of metal, and also to inclose the ventilating-chamber with the heating-pipes C' within a single passage, C. When this is done the heat that radiates from the pipes assists in heating the ventilating-chamber, which materially increases the draft both in the smoke- 20 pipe and also in the ventilating-stack.

Having thus described my process and mechanism, what I claim is—

1. In combination with a hot-air chamber, the furnace-pipes leading to different floors 25 of the building, said pipes being provided with adjusting-plates, whereby heat may be taken from any plane in the hot-air chamber desired, substantially as and for the purposes shown and described.

2. The combination, with a hot-air chamber and heat-conducting pipes, of intermediate pipes, respectively connecting the two former parts, said intermediate pipes being adapted to be vertically adjusted, substantially as set 30 forth.

In testimony whereof I have signed my name to this specification in the presence of two subscribing witnesses.

WILLIAM F. BEECHER.
